UNITED STATES PATENT OFFICE.

WILLIAM S. CRAIG, OF MONROE, MICHIGAN, ASSIGNOR TO CRAIG ENGINEERING COMPANY, OF MONROE, MICHIGAN, A CORPORATION OF MICHIGAN.

GEARING FOR GLUE-SPREADERS.

1,025,376.

Specification of Letters Patent.

Patented May 7, 1912.

Application filed July 17, 1911. Serial No. 638,844.

To all whom it may concern:

Be it known that I, WILLIAM S. CRAIG, a citizen of the United States, residing at Monroe, in the county of Monroe and State 5 of Michigan, have invented certain new and useful Improvements in Gearing for Glue-Spreaders; and I do declare the following to be a full, clear, and exact description of the invention, such as will enable others 10 skilled in the art to which it appertains to make and use the same, reference being had to the accompanying drawings, and to the letters and figures of reference marked thereon, which form a part of this specification. 15

This invention relates to new and useful improvements in gearing especially adapted for glue spreaders and cookers, of the type used in veneer stock production, and other 20 work requiring the application of glue.

More particularly the invention relates to the gearing for the glue-spreading rollers.

The object of the invention is to provide improvements whereby simplicity and efficiency combine in the machine to a desirable extent. 25

Through the means provided, the spreading rollers are adapted to be positively driven at the same rate of speed though 30 their distances apart may vary. This allows the rollers to be adjusted with facility to suit different thicknesses of material to be coated with glue, for example, the sheets from which veneer work is made.

35 Referring to the accompanying drawings, Figure 1 is a front elevation of a glue spreading machine provided with my improvements; and Fig. 2 is an end elevation of the same.

40 Referring more particularly to the drawings, 1 represents a lower glue container which may be steam heated by the usual means, and which is supported upon a frame 2. Mounted above the container 1, is a

45 lower glue-spreading roller 3, the lower surface of which is adapted to be immersed in the glue within the container 1. The said roller 3 is mounted on a shaft 4 journaled in bearings 5 attached to the upper side of the glue container 1. Also mounted 50 on the upper side of the container 1, are frame members 5^a provided with vertical guide openings 6 at the ends of the machine.

55 Mounted in each opening 6 is an adjustable bearing 7 which receives a shaft 8 upon

which the upper spreading roller 9 is mounted. Also mounted within the openings 6 above the bearings 7, are sliding supporting blocks 10, provided with brackets 11 which support an upper glue receptacle 60 12. The receptacle 12 may be steam jacketed in the usual manner, and supplies the liquid glue to the upper spreading roll 9. The blocks 10 rest upon the bearings 7, and are therefore movable therewith; therefore, 65 when the upper roller 9 is elevated or depressed, the glue receptacle 12 will move in unison therewith. The wood or other material to be glued is passed between the upper and lower rollers, and the upper roller 70 is adjustably mounted to permit wood sheets of different thicknesses to pass through the machine.

The above description relates to one well known type of glue spreader, the various 75 details of which may be altered without affecting the present invention.

The upper and lower rollers 9 and 3 may be rotated at the same speed in opposite directions, and elevated and lowered by the 80 following mechanism at the same time, or elevated and lowered while not rotating. The ends of the upper shaft 8 and the lower shaft 4 are connected by toggle joints formed by upper and lower links 13 and 14 which 85 are connected at pivots 15. Attached to the pivots 15 are reaches or bars 16 which extend around the rear side of the machine, and are pivotally attached to a threaded sleeve 17. The sleeve 17 is mounted on a 90 screw shaft 18 journaled in a bearing 19 and provided with a hand wheel 20. When the hand wheel 20 is rotated, the sleeve 17 is reciprocated, and the angle formed by the links 13 and 14 will be varied. When the 95 toggle joints are thus actuated, the rollers 3 and 9 will be elevated and depressed. To rotate the rollers 3 and 9 at the same speed and in opposite directions, there are mounted on the shafts 4 and 8 gears 21 and 22 respectively, which are of the same size; and mounted between the said gears 21 and 22 are two idlers 23 and 24. As the train of gearing thus constituted, consists of an even 100 number of gears, the rolls 3 and 9 will rotate in opposite directions. The idler gears 23 and 24 are mounted on one of the toggle links, the gear 23 being mounted on the pivot 15, while the gear 24 is mounted on the link 14. The axes of the intermeshing 110

gears are therefore always the same distance apart irrespective of the position of the toggle joints; therefore the gears will always be in mesh.

5 The rollers 3 and 9 are driven from a pulley 25 mounted on a shaft 26 journaled in a bracket 27. The shaft 26 carries a gear 28 which meshes with the gear 21 on the shaft 4 carrying the roller 3; the upper roller 9 10 being driven from the gear 21 through the train of gearing above described.

Having described my invention, I claim:

1. In a device of the type specified, a frame, an upper and a lower roller mounted 15 in said frame, toggle links connecting said rollers, means for varying the relative positions of said rollers by varying the angle of said links, and means on said links adapted to rotate one of said rollers in unison with the other.

2. In a device of the type specified, a frame, an upper and a lower roller mounted in said frame, toggle links connecting said upper and lower rollers and adapted to vary 25 their relative positions, gears connected to said rollers, intermediate driving gears mounted between said first named gears, and mounted on said toggle links, whereby said rollers may rotate in unison, and means for

varying the angle of said toggle links to 30 change the relative positions of the rollers.

3. In a device of the type specified, a frame, an upper and a lower roller mounted in said frame, toggle links connecting said rollers and adapted to vary their relative 35 positions, bars attached to said toggle links at the pivots thereof, a threaded sleeve to which said bars are attached, and a threaded shaft adapted to actuate said sleeve to vary the angle of said toggle links.

4. In a device of the type specified, a frame, an upper and a lower roller mounted in said frame, toggle links connecting said rollers and adapted to change their relative positions, bars attached to said toggle links 45 at their pivots, a threaded sleeve to which said bars are attached, a threaded shaft adapted to actuate said sleeve to vary the angle of said links, gears operatively attached to said rollers, and idler gears 50 mounted between said first named gears on said toggle links.

In testimony whereof I affix my signature, in presence of two witnesses.

WILLIAM S. CRAIG.
